CEILING BOARD JACK

Ira Sellers, Walla Walla, Wash.

Application August 28, 1947, Serial No. 771,060

4 Claims. (Cl. 304—29)

1

The invention aims to provide an effective, durable and safe jack enabling one man to lift sheets of ceiling board and hold them in place while they are being nailed, and in carrying out this end, a further object is to provide a jack which is not only extensible and retractable due to the provision of telescoped standard sections, but due to the provision of vertically adjustable legs for a base which supports the standard.

Figure 1 of the accompanying drawings is a side elevation of the jack.

Fig. 2 is an end elevation.

Fig. 3 is an enlarged vertical longitudinal section on line 3—3 of Fig. 2.

Figs. 4 and 5 are horizontal sectional views on the correspondingly numbered lines of Fig. 3.

Fig. 6 is a horizontal sectional view on line 6—6 of Fig. 3.

A preferred construction has been illustrated in the drawings and will be rather specifically described, but it is to be understood that within the scope of the invention as claimed, numerous minor variations may be made.

A horizontal base 7 is provided having vertically adjustable legs 8, said legs having casters 8' allowing the entire device to be readily moved into proper position upon a floor and also permitting it to be rolled from one room to another. A lower tubular standard section 9 is secured at its lower end to the base 7, an upper standard section 10 is slidably telescoped with said lower section 9, and a horizontal ceiling board supporting frame 11 is carried by the upper end of said upper standard section 10; and provision is made for raising and lowering the section 10 and for holding it in adjusted position.

The base 7 includes a flat horizontal rectangular frame 12 having parallel side bars 13 and parallel end bars 14 integrally joined to each other, said frame being rectangular as shown in Fig. 6. The side and end bars 13 and 14 may well be formed from two lengths of flat or bar metal bent into U-shape and having their ends secured together by splice plates 15 riveted or otherwise secured in place at the centers of the side bars 13.

The legs 8 which are formed of rectangular bars having flat outer faces, are all disposed vertically within the corners of the frame 12, and angular yoke plates 16 engage the inner sides of said legs and are secured to the frame side and end bars by bolts or the like 17. When these bolts are loosened, the frame 12 may be vertically adjusted with respect to the legs 8, and said frame and legs may be then clamped and

2

locked against relative movement by tightening said bolts.

In the construction shown, the upper edges of the splice plates 15 are provided with inwardly projecting horizontal flanges 18 upon which a transverse horizontal plate 19 is secured by bolts or the like 20. One of these bolts also secures the lower end of an inclined standard brace 21, and another similar brace 22 is secured by a bolt or the like 23 to a bracket 24 riveted or otherwise secured to one of the end bars 14 of the base frame 12.

The tubular lower standard section 9 includes two longitudinal semi-cylindrical halves 25 having flanges 26 at their lower ends riveted or otherwise secured to the transverse plate 19. The longitudinal edges of the halves 25 are spaced apart to provide the lower standard section 9 with two diametrically opposed slots 27 and 28, and the upper ends of said halves 25 are riveted or otherwise secured to a collar 29. The upper end of the brace 22 is secured to this collar and the upper end of brace 21 may be suitably secured to one of the halves 25. This collar is provided with an internal notch 29' wider than the slot 28 and communicating with the latter, for a purpose to appear.

Two short horizontal bars 30 and 31 are riveted or otherwise secured to the outer sides of the halves 25 of the lower standard section 9, respectively, said bars being disposed in parallel relation with each other and located equidistantly below the collar 29. A vertical plate 32 is suitably secured to and projects downwardly from the bar 30, and the lower end of this plate is secured at 33 to one of the halves 25. A transverse horizontal shaft 34 extends through the bars 30 and 31, at one end of these bars, and extends also through the plate 32. A gear 35 is secured on the central portion of this shaft 34, a ratchet wheel 36 is secured on one end of said shaft and located at the outer side of the bar 31, and another gear 37 is secured on the other end of said shaft and located at the outer side of the plate 32. A driving gear 38 meshes with the gear 37 and is mounted at 39 upon the plate 32, said driving gear having an operating crank 40.

A dog 41 is cooperable with the ratchet wheel 36 and is mounted upon the outer side of the bar 31, said dog having a tail 42 instrumental in releasing it. A dog-releasing shaft 43 extends through the end portions of the bars 31 and 30 opposite the shaft 34 and is provided on one end with a lug 44 overlying the tail 42, the other

end of said shaft 43 being formed with an operating handle 45. When this handle is turned in the proper direction, the lug 44 presses downwardly upon the tail 42, thereby releasing the dog 41 from the ratchet wheel 36.

The upper standard section 10 is tubular and cylindrical and is formed with a longitudinal slot 46 which communicates with the slot 27. The gear 35 extends through both of these slots and meshes with a vertical rack bar 47 within the standard section 10. This rack bar abuts diametrically opposite portions of this standard section, at opposite sides of the slot 46, and is secured to said section by rivets or the like shown at 48 in Fig. 3. The standard section 10 has a longitudinal rib 49 secured thereto and slidably received in the slot 28 of the lower standard section 9 to prevent rotation of section 10 with respect to said section 9. A vertically elongated metal strip 50 is secured against the outer side of the rib 49 and contacts slidably with the peripheral portions of the halves 25 of the section 9, adjacent the slot 28. This strip 50 extends through the notch 29' of the collar 29.

It is preferable to secure a suitable hand-grip 51 to the plate 32, to be gripped by one hand, to steady the entire device, while operating the crank 40 with the other hand. When this crank is turned clockwise, it drives the gearing to elevate the upper standard section 10, said gearing being locked against retrograde rotation by means of the ratchet wheel 36 and dog 41, to hold the upper standard section in any upwardly extended position to which it may be raised. When this section is to be again lowered, the dog is released by turning the handle 45 of the shaft 43, the crank 40 being then turned retrogradely. The lower end of the lower standard section 9 is of course open, and the supporting plate 19 is formed with an opening 52 communicating with the interior of said standard section 9, thus permitting the upper section 10 to be lowered to a position in which it will project downwardly to some extent from said upper section 9, thereby permitting maximum lowering of the ceiling board supporting frame 11, to facilitate placing of a sheet of ceiling board upon this frame. By having the adjustable legs 8 extend both above and below the base 12 and by making the upper standard longer than the lower standard so that its lower end may extend through the opening 52, an extensive range of vertical adjustment of the frame or platform 11 can be obtained. Also by making the base 12 of elongated rectangular shape and the frame 11 removable, the device may be readily moved through door openings. The particular construction of the device makes it very strong and sturdy, so that it can be used as a scaffold.

From the foregoing, taken in connection with the accompanying drawings, it will be seen that novel and advantageous provision has been made for attaining the desired end, and while preferences have been illustrated, attention is again invited to the possibility of making variations within the scope of the invention as claimed.

I claim:

1. A ceiling board jack comprising a substantially flat and rectangular base, vertically adjustable legs at the corners of said base, said legs extending through and having their ends extending both above and below said base, means for securing said legs in adjusted positions, a centrally apertured supporting member carried by said base and disposed at its center, a lower

tubular standard having a longitudinal slot and being secured to and rising from said supporting member, the ends of said standard being open and its lower open end being aligned with said aperture, an upper tubular standard of greater length than said lower standard slidably telescoped in the open upper end of said lower standard and having its lower end movable downwardly through said aperture, said upper standard having a longitudinal slot to register with the slot in the lower standard, a ceiling board supporting frame carried by the upper end of said upper standard, and means carried by said lower standard for vertically adjusting said upper standard and securing it in an adjusted position, the last named means comprising a toothed gear rotatably mounted on said upper standard and having a portion projecting through said registering slots, a rack bar fixed within said upper standard and in mesh with said gear, means for rotating said gear and releasable means for holding said gear against rotation in one direction.

2. A ceiling board jack comprising a substantially flat and rectangular base composed of opposed side and opposed end bars having flat vertically disposed inner faces, vertically adjustable leg bars at the corners of said base, said leg bars extending through and having their ends extending both above and below said base, said leg bars being of rectangular shape in cross section with flat faces, each of said leg bars having two of its flat surfaces in slidable contact with the flat inner faces of said base bars at a corner of the base, angular clamping yokes engaged with the said flat faces of said leg bars, bolts securing said yokes to the bars of said base to clamp said leg bars against said base bars, a centrally apertured supporting member carried by said base and disposed at its center, a lower hollow standard secured to and rising from said supporting member, the ends of said standard being open and its open lower end being aligned with said aperture, an upper standard of greater length than said lower standard slidably telescoped in the open upper end of said lower standard and having its lower end movable downwardly through said aperture, a ceiling board supporting frame carried by the upper end of said upper standard, and means carried by said lower standard for vertically adjusting said upper standard and securing it in an adjusted position.

3. A ceiling board jack comprising a base, a lower tubular standard section secured to and projecting upwardly from said base, said lower standard section being composed of two longitudinal halves having their edges spaced apart to provide opposed longitudinal slots, and a collar around and secured to the upper ends of said halves to hold them in spaced relation; one horizontal bar secured between its ends against the outer side of one of said halves, a second horizontal bar secured between its ends against the outer side of the other of said halves, said bars being located equidistantly below said collar and being disposed at opposite sides of said slots, a shaft extending through said bars at one end of the latter, one gear secured on said shaft at the outer side of one of said bars, a ratchet wheel secured on said shaft at the outer side of the other of said bars, another gear secured on said shaft between said bars and extending through one of the aforesaid opposed slots, a vertical plate secured to the outer side

of said one of said bars and projecting downwardly therefrom, a driving gear mounted on said vertical plate and meshing with the aforesaid one gear, said driving gear having an operating crank, a dog mounted on said other of said bars and engaging said ratchet wheel to prevent retrograde rotation thereof until released; an upper tubular standard section telescoped within the aforesaid lower section and having ceiling board supporting means, means on said upper standard and slidably engaged with the other of said opposed slots, and a vertical rack within and connected with said upper section and engaging the teeth of the aforesaid other gear.

4. A ceiling board jack comprising a base, a lower tubular standard section secured to and projecting upwardly from said base, said lower standard section being composed of two longitudinal halves having their edges spaced apart to provide opposed longitudinal slots, and a collar around and secured to the upper ends of said halves; an upper tubular standard section telescoped with said lower section and having ceiling board supporting means, said upper section having a slot to register with one of said opposed slots and a longitudinal rib slidably received in the other of said opposed slots, a

gear extending through said registering slots and mounted on said lower standard section, a rack bar within and connected with said upper standard section and engaging said gear, a vertical strip secured to the outer edge of said rib and extending substantially throughout the length thereof, said strip being transversely curved and contacting slidably with the outer sides of said halves of said lower standard section, said collar having an internal notch through which said strip extends and means for driving said gear to elevate and lower said upper standard section.
